UNITED STATES PATENT OFFICE

EDGAR W. PATTERSON, OF LOS ANGELES, CALIFORNIA, ASSIGNOR, BY MESNE ASSIGNMENTS, TO CLAYTON SEVERNS AND J. N. HICKS

OIL SAVER

Application filed December 5, 1930. Serial No. 500,364.

This invention relates to an oil saver which may be secured to the upper end of a well casing and through which a cable may work up and down, the cable being packed to prevent loss of oil through the casing and around the cable. Such savers are commonly used with percussive drilling in oil sands, swabbing and bailing. Packed heads for saving oil have heretofore been provided and so constructed that a cap forming a part thereof will be released upon a swell in the cable, such as a socket, striking the head. Such structures have been designed to prevent damage and breakage of the cable when the cable and appended tools pass beyond their normal upper limit of travel.

The present invention appertains to an oil saver head of the character above described. It has for its principal object the provision of a releasable cap which is positively locked in normal operating position, and has for a more specific object the provision of details of structure enabling among other things a well packed head.

These objects are obtained by means of the embodiment of my invention shown in the accompanying drawings, in which:—

Fig. 1 is a vertical axial section through an oil saver; Figs. 2 and 3 are sections as seen on the lines correspondingly numbered in Fig. 1; Fig. 4 is a perspective view of the retainer thimble; Fig. 5 is a perspective view of the catch barrel; and Fig. 6 is a sectional view showing a fragment of a cap and nipple section embodying a modified form of the invention.

Referring more particularly to Figs. 1 to 5, the upper end of a well casing is marked 7 and has threaded therein a tubular body 8 forming a part of a nipple section. The body has an inner bevel at its upper end and is externally reduced in diameter with a shoulder 9, there being an external thread adjacent the shoulder. Intermediate the ends of the body is an annular groove 10 having sloping sides. These sides form inclined surfaces for coaction with a catch. A collar 11 is secured on the body 8 abutting the shoulder providing an annular space 12 between the body and the collar. The collar has a

bore of enlarged diameter adjacent the top and is internally threaded as denoted by 13. Threaded into the collar is a ring 14 having a key 15. A ring leather packing 16 is clamped between the ring 14 and the collar.

A cap 17 is arranged to slip into the ring 14 and has a skirt 18 to slip over the body and to be engaged externally by the free lip of the ring leather 16.

A detent key 19 is mounted in the cap and held outwardly by a spring engaging in the key way and locks the cap against rotation with respect to the nipple section. The leather 16 prevents a leakage of fluid between the body 8, skirt 18 through the joint found between the ring 14 and the cap 17. The crown of the cap is marked 20 and has a stuffing box with packing 21 held in place by a gland 22 and a gland nut 23 threaded to the crown 20 and having handles for adjustment of the packing.

Disposed within the bore of the cap 17 and depending therefrom is a catch barrel 24 threaded at its upper end so as to be engaged with a corresponding thread in the cap and locked in position by a set screw 25. The barrel is made of spring material and is slotted to provide spring fingers 26 having an axial line of flexure. At the tips of the fingers are mounds 27 having inclined surfaces corresponding to the inclined surfaces in the groove 10. Ledges 28 are provided on the inner faces of the fingers adjacent their tips. Disposed within the barrel 24 and embraced by the fingers 26 is a retainer member 29 having a reduced portion 29a for unlocking and an enlarged portion 29b for locking the fingers. A shoulder is provided intermediate the reduced and enlarged portions for seating upon the ledges 28 at the fingers. A bore 30 for the passage of a cable 31 is enlarged at the upper end to provide a socket 30a for reception of a spring 32 of the compression type tending to project the thimble downwardly with the enlarged portion between the fingers as shown in Fig 1. The thimble may be raised against the action of spring 32 to dispose the reduced portion 29a between the fingers, whereupon the latter may be flexed inwardly and the cap 17 released from

80
85
90
95
100

the nipple section. On the cable is a swell 31a which may be engaged with the thimble.

The oil saver is assembled with the parts 5 normally in the position shown in Fig. 1 and mounted upon the top of the well casing. The retainer thimble maintains the fingers 26 with their mounds 27 in the recess 30, the inclined surfaces coacting so that the oil saver is securely locked in position. The 10 cable may be raised and lowered, but if it is raised so that the socket 31a engages the retainer thimble, the latter will be raised to release the fingers and a further upward pull on the cable will cause the cap 17 to be lifted, 15 the fingers riding out of the recess 10. Thus, any undue strain on the cable or part of the oil saver will be prevented. In restoring the oil saver to normal operating position, the thimble 29 is raised and the cap fixed into 20 position, the ring 16 securely packing it. The shoulders 26 on the fingers will hold retainer in released position until the mounds of the fingers ride into the recess 10. Thereupon, the spring 32 will position the retainer in 25 locking position as shown in Fig. 1.

Referring particularly to Fig. 6, the nipple body 8 is of the same structure as before described, the collar 33 corresponding to collar 11 being attached thereto and a bore 30 thereof being smooth. Cap 34 corresponding to cap 17 slips within the collar 33 and over the body 8. A catch barrel 24 is of the same structure as previously described. It will be noted that there is no member 35 corresponding to ring 14. Ring packing 35 is disposed in the slot between the collar and body and disposed in packing position by a compression spring 36. The downward extension 18a of the cap 34 corresponds with 40 the skirt 18 of Fig. 1. The operation is obvious from the assembled structure described.

What I claim is:—

1. An oil saver comprising a nipple section 45 adapted to be attached to the top of a well casing, a cap detachably mounted in said nipple section and having a packing for a cable to extend therethrough; resilient means mounted on said cap with inclined surfaces formed on said nipple section to yieldably secure said cap to said nipple section, a retainer disposed within and encompassed by said resilient means, said retainer being longitudinally movable and having spaced locking and un- 50 locking portions either of which is registerable with said resilient means whereby either to lock said resilient means to said nipple section in cap securing position or to unlock said resilient means, said retainer being urged into 55 locking position and arranged to have said cable pass therethrough whereby a swell in said cable may engage said retainer and move the latter to unlocking position and thereby enable said cap to be detached from said nipple section.

2. An oil saver comprising a nipple section adapted to be attached to the top of a well casing, a cap detachably mounted in said nipple section and having a packing for a cable to extend therethrough; resilient means 70 mounted on to said cap with inclined surfaces acting on inclined surfaces formed on said nipple section to yieldably secure said cap to said nipple section, a retainer disposed within and encompassed by said resilient means, said retainer being longitudinally movable and having spaced locking and unlocking portions either of which is registerable with said resilient means whereby either to lock said resilient means to said nipple section in cap securing position or to unlock said resilient means, 75 spring means urging said retainer into locking position, said retainer being arranged to have said cable pass therethrough whereby a swell in said cable may engage said retainer and move the latter to unlocking position and thereby enable said cap to be detached from said nipple section.

3. An oil saver comprising a nipple section 80 adapted to be attached to the top of a well casing, a cap detachably mounted in said nipple section and having a packing for a cable to extend therethrough; resilient fingers mounted on to said cap and having an axial line of flexure, said fingers having inclined 85 surfaces acting on inclined surfaces formed on said nipple section to yieldably secure said cap to said nipple section, a retainer disposed within and encompassed by said fingers, said retainer being longitudinally movable and having spaced locking and unlocking portions either of which is registerable with said fingers whereby either to lock said fingers to said nipple section in cap securing position or to unlock said fingers, 90 said retainer being urged into locking position and arranged to have said cable pass therethrough whereby a swell in said cable may engage said retainer and move the latter to unlocking position and thereby enable said cap to be detached from said nipple section.

4. An oil saver comprising a nipple section 95 adapted to be attached to the top of a well casing, a cap detachably mounted in said nipple section and having a packing for a cable to extend therethrough; resilient fingers mounted on to said cap and having an axial line of flexure, said fingers having out- 100 standing mounds with inclined surfaces, said nipple section having a groove with inclined surfaces for coaction with said mounds to yieldably secure said cap to said nipple section, a retainer disposed within and encompassed by said fingers, said retainer being longitudinally movable and having spaced locking and unlocking portions either of which is registerable with said fingers whereby either to lock said fingers to said nipple section in cap securing position or to unlock 105 said fingers, said retainer being urged into 110 locking position and arranged to have said cable pass therethrough whereby a swell in said cable may engage said retainer and move the latter to unlocking position and thereby enable said cap to be detached from said nipple section.

5. An oil saver comprising a nipple section 115 adapted to be attached to the top of a well casing, a cap detachably mounted in said nipple section and having a packing for a cable to extend therethrough; resilient fingers mounted on to said cap and having an axial line of flexure, said fingers having out- 120 standing mounds with inclined surfaces, said nipple section having a groove with inclined surfaces for coaction with said mounds to yieldably secure said cap to said nipple section, a retainer disposed within and encompassed by said fingers, said retainer being longitudinally movable and having spaced locking and unlocking portions either of which is registerable with said fingers whereby either to lock said fingers to said nipple section in cap securing position or to unlock 125 said fingers, said retainer being urged into 130 locking position and arranged to have said cable pass therethrough whereby a swell in said cable may engage said retainer and move the latter to unlocking position and thereby enable said cap to be detached from said nipple section.

locking position and arranged to have said cable pass therethrough whereby a swell in said cable may engage said retainer and move the latter to unlocking position and thereby enable said cap to be detached from said nipple section.

5. An oil saver comprising a nipple section adapted to be attached to the top of a well casing, a cap detachably mounted in said nipple section and having a packing for a cable to extend therethrough; a barrel secured to and depending from said cap, said barrel having axially extending spring fingers with outstanding mounds having inclined surfaces, a groove in said nipple section having inclined surfaces for coaction with the mounds on said fingers whereby to yieldably secure said cap to said nipple section, a retainer thimble disposed within and encompassed by said resilient means, said thimble being longitudinally movable and having longitudinally spaced locking and unlocking portions either of which is registerable with said fingers whereby either to lock said spring fingers to said nipple section in cap securing position or to unlock said spring fingers, a compression spring urging said thimble into locking position and arranged to have said cable pass therethrough whereby a swell in said cable may engage said thimble and move the latter to unlocking position and thereby enable said cap to be detached from said nipple section.

6. An oil saver comprising a nipple section adapted to be attached to the top of a well casing, said nipple section including a tubular body and an upstanding collar at the top providing an annular space therebetween, a slip-in cap having a depending skirt engaging over said body and within said space, an annular packing leather disposed in said space, said cap having a packing for a cable to extend therethrough; catch means mounted on to said cap with surfaces for coaction with surfaces formed on said body to secure said cap to said nipple section, a retainer disposed within and encompassed by said catch means, said retainer being longitudinally movable and having spaced locking and unlocking portions either of which is registerable with said catch means whereby either to lock said catch means to said nipple section in cap securing position or to unlock said catch means, said retainer being urged into locking position and arranged to have said cable pass therethrough whereby a swell in said cable may engage said retainer and move the latter to unlocking position and thereby enable said cap to be detached from said nipple section.

7. An oil saver comprising a nipple section adapted to be attached to the top of a well casing, said nipple section including a tubular body and an upstanding collar at the top providing an annular space therebe-

tween, a slip-in cap having a depending skirt engaging over said body and within said space, an annular packing leather disposed in said space, said cap having a packing for a cable to extend therethrough; resilient means mounted on said cap with inclined surfaces formed on said body to yieldably secure said cap to said nipple section, a retainer disposed within and encompassed by said resilient means, said retainer being longitudinally movable and having spaced locking and unlocking portions either of which is registerable with said resilient means whereby either to lock said resilient means to said nipple section in cap securing position or to unlock said resilient means, said retainer being urged into locking position and arranged to have said cable pass therethrough whereby a swell in said cable may engage said retainer and move the latter to unlocking position and thereby enable said cap to be detached from said nipple section.

8. An oil saver comprising a nipple section adapted to be attached to the top of a well casing, said nipple section including a tubular body and an upstanding collar at the top providing an annular space therebetween, a slip-in cap having a depending skirt engaging over said body and within said space, an annular packing leather disposed in said space, said cap having a packing for a cable to extend therethrough; resilient means mounted on said cap with inclined surfaces acting on inclined surfaces formed on said body to yieldably secure said cap to said nipple section, a retainer disposed within and encompassed by said resilient means, said retainer being urged into locking position and arranged to have said cable pass therethrough whereby a swell in said cable may engage said retainer and move the latter to unlocking position and thereby enable said cap to be detached from said nipple section.

9. An oil saver comprising a nipple section adapted to be attached to the top of a well casing, said nipple section including a tubular body and an upstanding collar at the top providing an annular space therebetween, a slip-in cap having a depending skirt engaging over said body and within said space, an annular packing leather disposed in said space, said cap having a packing for a cable to extend therethrough; resilient fingers mounted on to said cap and having an axial line of flexure, said fingers having inclined surfaces acting on inclined surfaces formed on said body to yieldably secure said cap to

- said nipple section, a retainer disposed within and encompassed by said fingers, said retainer being longitudinally movable and having spaced locking and unlocking portions 6 either of which is registerable with said fingers whereby either to lock said fingers to said nipple section in cap securing position or to unlock said fingers, said retainer being urged into locking position and arranged to 10 have said cable pass therethrough whereby a swell in said cable may engage said retainer and move the latter to unlocking position and thereby enable said cap to be detached from said nipple section.
- 15 10. An oil saver comprising a nipple section adapted to be attached to the top of a well casing, said nipple section including a tubular body and an upstanding collar at the top providing an annular space there- 20 between, a slip-in cap having a depending skirt engaging over said body and within said space, an annular packing leather disposed in said space, said cap having a pack- ing for a cable to extend therethrough; re- 25 silient fingers mounted on to said cap and having an axial line of flexure, said fingers having outstanding mounds with inclined surfaces, said body having a groove with inclined surfaces for coaction with said 30 mounds to yieldably secure said cap to said nipple section, a retainer disposed within and encompassed by said fingers, said re- tainer being longitudinally movable and hav- 35 ing spaced locking and unlocking portions either of which is registerable with said fin- gers whereby either to lock said fingers to said nipple section in cap securing position or to unlock said fingers, said retainer being urged into locking position and arranged to 40 have said cable pass therethrough whereby a swell in said cable may engage said retainer and move the latter to unlocking position and thereby enable said cap to be detached from said nipple section.
- 45 11. An oil saver comprising a nipple section adapted to be attached to the top of a well casing, said nipple section including a tubular body and an upstanding collar at the top providing an annular space therebetween, 50 a slip-in cap having a depending skirt en- gaging over said body and within said space, an annular packing leather disposed in said space, said cap having a packing for a cable to extend therethrough; a barrel secured to 55 and depending from said cap, said barrel hav- ing axially extending spring fingers with out- standing mounds having inclined surfaces, a groove in said body having inclined surfaces for coaction with the mounds on said fingers 60 whereby to yieldably secure said cap to said nipple section, a retainer thimble disposed within and encompassed by said resilient means, said thimble being longitudinally movable and having longitudinally spaced 65 locking and unlocking portions either of
- which is registerable with said resilient means whereby either to lock said spring fingers to said nipple section in cap securing position or to unlock said spring fingers, a compression spring urging said thimble into locking position and arranged to have said cable pass therethrough whereby a swell in said cable may engage said thimble and move the latter to unlocking position and thereby enable said cap to be detached from said nip- 70 ple section. 75
12. An oil saver comprising a nipple section adapted to be attached to the top of a well casing, said nipple section including a tubular body and an outstanding collar threaded to the top of said body providing an annular space therebetween, said collar having a shoulder in its bore, a ring threaded into the bore of said collar, a slip-in cap mounted within the bore of said ring and hav- 80 ing a depending skirt engaging over said body and within said space, an annular pack- ing leather disposed in said space, and clamped between said ring and collar at said shoulder, said cap having a packing for a cable to extend therethrough; catch means mounted on to said cap with surfaces for co- 85 action with surfaces formed on said body to secure said cap to said nipple section, a re- tainer disposed within and encompassed by 90 said catch means, said retainer being longi- tudinally movable and having spaced lock- ing and unlocking portions either of which is registerable with said catch means where- 95 by either to lock said catch means to said nip- ple section in cap securing position or to un- lock said catch means, said retainer being urged into locking position and arranged to have said cable pass therethrough whereby a swell in said cable may engage said retainer and move the latter to unlocking position and thereby enable said cap to be detached from 100 said nipple section. 105
13. An oil saver comprising a nipple section adapted to be attached to the top of a well casing, said nipple section including a tubular body and an upstanding collar threaded to the top of said body providing an annular space therebetween, said collar hav- 110 ing a shoulder in its bore, a ring threaded into the bore of said collar, a slip-in cap mounted within the bore of said ring having a depend- 115 ing skirt engaging over said body and within said space, an annular packing leather dis- posed in said space and clamped between said ring and collar at said shoulder, said cap hav- 120 ing a packing for a cable to extend there- through; resilient means mounted on said cap with inclined surfaces formed on said body to yieldably secure said cap to said nipple section, a retainer disposed within and en- 125 compassed by said resilient means, said re- tainer being longitudinally movable and hav- 130 ing spaced locking and unlocking portions either of which is registerable with said re-

- silient means whereby either to lock said resilient means to said nipple section in cap securing position or to unlock said resilient means, said retainer being urged into locking position and arranged to have said cable pass therethrough whereby a swell in said cable may engage said retainer and move the latter to unlocking position and thereby enable said cap to be detached from said nipple section. 10
14. An oil saver comprising a nipple section adapted to be attached to the top of a well casing, said nipple section including a tubular body and an upstanding collar threaded to the top of said body providing an annular space therebetween, said collar having a shoulder in its bore, a ring threaded into the bore of said collar, a slip-in cap mounted within the bore of said ring having a depending skirt engaging over said body and within said space, an annular packing leather disposed in said space and clamped between said ring and collar at said shoulder, said cap having a packing for a cable to extend therethrough; resilient means mounted on said cap with inclined surfaces acting on inclined surfaces formed on said body to yieldably secure said cap to said nipple section, a retainer disposed within and encompassed by said resilient means, said retainer being longitudinally movable and having spaced locking and unlocking portions either of which is registerable with said resilient means whereby either to lock said resilient means to said nipple section in cap securing position or to unlock said resilient means, spring means urging said retainer into locking position, said retainer being arranged to have said cable pass therethrough whereby a swell in said cable may engage said retainer and move the latter to unlocking position and thereby enable said cap to be detached from said nipple section. 15
15. An oil saver comprising a nipple section adapted to be attached to the top of a well casing, said nipple section including a tubular body and an upstanding collar threaded to the top of said body providing an annular space therebetween, said collar having a shoulder in its bore, a ring threaded into the bore of said body, providing an annular space therebetween, said collar having a shoulder in its bore, a ring threaded into the bore of said collar, a slip-in cap mounted within said bore having a depending skirt engaging over said body and within said space, an annular packing leather disposed in said space and clamped between said ring and collar at said shoulder, said cap having a packing for a cable to extend therethrough; resilient fingers mounted on to said cap and having an axial line of flexure, said fingers having outstanding mounds with inclined surfaces, said body having a groove with inclined surfaces for coaction with said mounds to yieldably secure said cap to said nipple section, a retainer disposed within and encompassed by said fingers, said retainer being longitudinally movable and having spaced locking and unlocking portions either of which is registerable with said fingers whereby either to lock said fingers to said nipple section in cap securing position or to unlock said fingers, said retainer being urged into locking position and arranged to have said cable pass therethrough whereby a swell in said cable may engage said retainer and move the latter to unlocking position and thereby enable said cap to be detached from said nipple section. 20
16. An oil saver comprising a nipple section adapted to be attached to the top of a well casing, said nipple section including a tubular body and an upstanding collar threaded to the top of said body providing an annular space therebetween, said collar having a shoulder in its bore, a ring threaded into the bore of said body, a slip-in cap mounted within the bore of said ring, having a depending skirt engaging over said body and within said space, an annular packing leather disposed in said space and clamped between said ring and collar at said shoulder, said cap having a packing for a cable to extend therethrough; resilient fingers mounted on to said cap and having an axial line of flexure, said fingers having outstanding mounds with inclined surfaces, said body having a groove with inclined surfaces for coaction with said mounds to yieldably secure said cap to said nipple section, a retainer disposed within and encompassed by said fingers, said retainer being longitudinally movable and having spaced locking and unlocking portions either of which is registerable with said fingers whereby either to lock said fingers to said nipple section in cap securing position or to unlock said fingers, said retainer being urged into locking position and arranged to have said cable pass therethrough whereby a swell in said cable may engage said retainer and move the latter to unlocking position and thereby enable said cap to be detached from said nipple section. 25
17. An oil saver comprising a nipple section adapted to be attached to the top of a well casing, said nipple section including a tubular body and an upstanding collar threaded to the top of said body providing an annular space therebetween, said collar having a shoulder in its bore, a ring threaded into the bore of said collar, a slip-in cap mounted within the bore of said ring having a depending skirt engaging over said body and within said space, an annular packing leather disposed in said space and clamped between said ring and collar at said shoulder, said cap having a packing for a cable to extend therethrough; a barrel secured to and depending from said cap, said barrel having axially extending spring fingers with outstanding mounds having inclined surfaces, a groove in said body having inclined surfaces for coaction with 30

- the mounds on said fingers whereby to yieldably secure said cap to said nipple section, a retainer thimble disposed within and encompassed by said resilient means, said thimble being longitudinally movable and having longitudinally spaced locking and unlocking portions either of which is registerable with said resilient means whereby either to lock said spring fingers to said nipple section in cap securing position or to unlock said spring fingers, a compression spring urging said thimble into locking position and arranged to have said cable pass therethrough whereby a swell in said cable may engage said 5 thimble and move the latter to unlocking position and thereby enable said cap to be detached from said nipple section.
18. An oil saver comprising a tubular lower section attachable to the top of a well casing, a cap detachably mounted upon said lower section and having a passage for a cable to extend therethrough; catch means mounted on to said cap with recesses in the upstanding walls of said tubular section for 10 coaction with surfaces which are inclined at their upper and lower sides and which are formed on said lower section to secure said cap thereto, and a longitudinally movable retainer disposed within said catch means and adapted at one longitudinal position to lock said catch means to said lower section in cap securing position and in another longitudinal position to unlock said catch means, whereby a part carried by said cable may 15 engage said retainer and move it to an unlocking position and thereby enable said cap to be detached from said lower section.
19. An oil saver comprising a nipple section adapted to be attached to the top of a well casing, said nipple section including a tubular body and an upstanding collar at 20 the top providing an annular space therebetween, a slip-in cap having a depending skirt engaging over said body and within said space, an annular packing disposed within said space externally of said skirt and between it and said collar, said cap having a packing for a cable to extend therethrough, and locking means for securing said cap to 25 said section releasable by a swell in said cable engaging said locking means.
20. An oil saver comprising a nipple section adapted to be attached to the top of a well casing, said nipple section including a tubular body and an upstanding collar threaded to the top of said body providing 30 an annular space therebetween, said collar having a shoulder in its bore, a ring threaded into the bore of said collar, a slip-in cap mounted within the bore of said ring having 35 a depending skirt engaging over said body and within said space, an annular packing disposed within said space and clamped between said ring and said collar at said shoulder, said packing being located externally of 40
- said skirt and between it and said collar, said cap having a packing for a cable to extend therethrough, and locking means for securing said cap to said section releasable by a swell in said cable engaging said locking means.
21. An oil saver comprising a nipple section adapted to be attached to the top of a well casing, a cap detachably mounted in 45 said nipple section and having a packing for a cable to extend therethrough; resilient means mounted on said cap with projecting portions acting on recesses having inclined surfaces formed on said nipple section to yieldably secure said cap to said nipple section, a retainer disposed within and encompassed by said resilient means, said retainer being longitudinally movable and having spaced locking and unlocking portions either of which is registerable with said resilient means whereby either to lock said resilient means to said nipple section in cap securing position or to unlock said resilient means, said retainer being urged into locking position and arranged to have said cable pass therethrough whereby a swell in said cable may engage said retainer and move the latter to unlocking position and thereby enable said cap to be detached from said nipple section.
- In witness that I claim the foregoing I have hereunto subscribed my name this 4th day of December, 1930.
- EDGAR W. PATTERSON.
